CLAIM

An ornamental design for a headphone, as shown and described.

DESCRIPTION

FIG. 1 is a first perspective view of an embodiment of a headphone.

FIG. 2 is a second perspective view of the embodiment of the headphone shown in FIG. 1.

FIG. 3 is a top view of the embodiment of the headphone shown in FIG. 1.

FIG. 4 is a bottom view of the embodiment of the headphone shown in FIG. 1.

FIG. 5 is a first side view of the embodiment of the headphone shown in FIG. 1.

FIG. 6 is a second side view of the embodiment of the headphone shown in FIG. 1, the second side being generally opposite to the first side shown in FIG. 5.

FIG. 7 is a front view of the embodiment of the headphone shown in FIG. 1; and,

FIG. 8 is a back view of the embodiment of the headphone shown in FIG. 1.

The broken lines immediately adjacent to the shaded areas represent the bounds of the claimed design while all other broken lines are directed to environment; the broken lines form no part of the claimed design.

1 Claim, 6 Drawing Sheets
